DESIGN.

—o—
T. HILL.

MUSICAL INSTRUMENT CASE.

No. 17,482.

Patented July 26, 1887.

UNITED STATES PATENT OFFICE.

THOMAS HILL, OF CHICAGO, ILLINOIS, ASSIGNOR TO STORY & CLARK, OF SAME PLACE.

DESIGN FOR A MUSICAL-INSTRUMENT CASE.

SPECIFICATION forming part of Design No. 17,482, dated July 26, 1887.

Application filed June 20, 1887. Serial No. 242,049. Term of patent 7 years.

To all whom it may concern:

Be it known that I, THOMAS HILL, a subject of the Queen of Great Britain, residing at Chicago, county of Cook, and State of Illinois, have invented and produced a new and original Design for Musical-Instrument Cases, of which the following is a specification, reference being had to the accompanying drawing, forming a part thereof.

10 The figure in the drawing is a perspective view from a rear corner of an organ case embodying my new design.

The essential features of my design are those which give a massive appearance to the case, 15 and chief of these are the pilasters A A A A, which are located against the back and ends of the case at the corners where their edges meet, and an open or hollow corner is formed between them, the plain base B, extending 20 from plinth to plinth of the corner pilasters, the heavy projecting cap C, surmounting the paneled dado D and extending from base to base of the pilasters, and the heavy overhanging cornice E, extending from capital to capital of the pilasters. The outline of the pilasters, as to the following particular details, 25 is also material to my design, viz: The plinth A' is plain. The die A² is recessed between the ends, leaving a square facet, A³, at the 30 upper end, just below the base. The base A³ is projecting and heavy, and its face is plainly molded in simple longitudinal curves. The shaft A⁴ is short and recessed between the ends like the die A², and terminates at the 35 upper end in a rectangular facet, A⁵, immediately below the capital A⁶, which is heavy and projecting, and has its face plainly molded in simple longitudinal curves. The entire pilaster from plinth to capital, including, 40 is of uniform width. The cheeks of the plinth, base, and capital, A², A³, and A⁶, respectively, are perfectly plane and parallel, as are also the entire sides of the pilaster of which said cheeks are part. The pilasters are 45 mounted by an entablature, F, which supports an ornamental frame-work, G, the details of which are not material to my design.

The cornice E, cap C, and base B are continued around the corner of the case, in the

open or hollow corner made between the pilasters, in the form of quarter-round brackets c, c, and b. The cornice E has a depending curtain, E', extending between the facets A¹⁰ of the shafts A¹.

I claim—

1. The design for a musical-instrument case herein shown and described, which comprises pilasters against the ends and back, located at the corners and meeting at their edges and forming a hollow corner, the plain base extending from plinth to plinth between the pilasters, the paneled dado extending between the pilasters from die to die, the heavy projecting cap above the dado extending between the pilasters from base to base, the overhanging cornice extending between the capitals and having the depending curtain between the shafts of the pilasters, and the entablature surmounting the pilasters and surmounted by an ornamental frame, G, the pilasters having a plain plinth, a recessed die, heavy projecting base, short recessed shaft, and smooth-faced projecting capital, and the base B, cap C, and cornice E being continued in quarter-rounds in the hollow corner formed by the pilasters at the corner of the case.

2. In a design for a musical-instrument case, the design for a pilaster herein shown and described, comprising a plain plinth, die recessed between its ends, having its face terminating in a rectangular facet at the upper end, smooth-faced base projecting and molded in simple longitudinal curves, short shaft recessed between its ends and terminating at the upper end in a rectangular facet, and a smooth-faced projecting capital molded in simple longitudinal curves, the sides of the pilaster being parallel and plain from plinth to capital, inclusive.

In testimony whereof I have hereunto set my hand at Chicago aforesaid, in the presence of two witnesses, this 11th day of June, A. D. 1887.

THOMAS HILL.

Attest:

CHAS. S. BURTON,
MELVILLE CLARK.
